John Glover,
Joseph B. Lawler, Attorney.

UNITED STATES PATENT OFFICE.

JOHN GLOVER, OF CHICAGO, ILLINOIS, ASSIGNOR TO O-CEDAR CORP'N., OF CHICAGO, ILLINOIS, A CORPORATION OF ILLINOIS.

MOP.

Application filed October 6, 1923. Serial No. 667,053.

My invention relates to new and useful improvements in mops and has for its principal object the formation thereof in such a manner that the mop strands or fabric may be removably received upon the mop frame and the handle may be detachably connected to the frame, said handle, when in position upon the frame, holding the mop strands or fabric against removal.

- 10 A further object of the invention resides in constructing the frame of wire or similar resilient material which is bent to form parallel arms to which the handle is detachably connected, the said parallel arms extending 15 inwardly towards the center of the frame so that when pressure is applied to the handle, in mopping, the proper contact of the mop strands or fabric will be secured with the floor or other object over which the mop 20 is being operated and the necessary pressure may be applied to the mop so as to properly clean the surface, the fact that the handle is connected approximately at the center point of the frame preventing tilting of the 25 mop during its movement over the object previously mentioned.

With the above and other objects in view, which will appear as the description proceeds, my invention consists in the novel design 30 tails of construction, and arrangement of parts, described in the following specification and illustrated in the accompanying drawings, and while I have illustrated and described the preferred embodiments of the 35 invention as they now appear to me, it will be understood that such changes may be made as will fall within the scope of the appended claims.

In the drawings:—

- 40 Fig. 1 is a top plan.
 Fig. 2 is a longitudinal vertical section through the brush with parts shown in elevation.
 Fig. 3 is a plan of the mop frame.
 45 Fig. 4 is a perspective of the connection between the handle and mop frame.
 Fig. 5 is an end view of the connection between the handle and mop frame, and
 50 Fig. 6 is a plan of the blank from which the connection between the handle and mop frame is formed.

In the drawings 1 indicates the frame which is preferably of the shape shown, and

is formed of round wire or other similar resilient material which is bent to form the inwardly extending parallel arms 2, the arms being normally spaced apart, as shown, and terminating at a point adjacent the center of the frame. Upon this frame is adapted to be received the mop fabric, said fabric comprising the loop or eye portion 3, through which the frame passes, and the strands 4 which are of the desired length for mopping purposes. It will readily be seen that the fabric may be easily placed upon the frame, or removed therefrom, so that when desired it may be washed or when worn may be replaced with a new one.

The mop handle is detachably connected to the frame and when in position upon the frame holds the mop fabric upon the frame against removal. The handle 5 has its lower end received in the socket member 6 which is pivotally connected at 7 to a plate 8 which is removably received upon the parallel extending arms 2. The plate 8 has its longitudinally extending edges inwardly curved as shown at 9 to provide the longitudinally extending eyes 10 through which the arms 2 pass. The plate 8 is transversely slit and from the slit portions are bent the lugs 11 which extend vertically, on the outside of the rolled portions 9, and are each provided with the openings 12 to receive the pivot pin 7, the lower end 13 of the socket 6 being received between the lugs and the pivot pin 7 extending transversely through the end portion 13 of the socket, the pivotal connection of the socket with the plate allowing for vertical swinging movement of the handle. Each of the parallel arms 2 is provided adjacent its end with a transversely extending opening 14 and a cotter pin 15 is adapted to pass through these openings 14 for securing the plate 8 upon the arms.

From the above detail description it is thought that the construction of the mop will be clearly understood and I will endeavor to go a little more fully into the manner of using. When the mop fabric is to be connected to the frame the cotter pin 15 is removed and the plate 8 slid upon the arms 2 to remove the arms from the eyes 10. With the plate removed the handle is dis-

connected and the mop fabric may be applied to the frame by threading the frame through the loop portion 3 of the fabric. With the fabric connected to the frame the 5 arms 2 are again slid through the eyes 10 of the plate 8 and the cotter pin 15 is reinserted through the openings 14 and by engaging the ends of the looped portions 9 of the plate 8 will hold the plate upon 10 the arms, the opposite ends of the looped portions 9 engaging the ends of the mop fabric as shown. The handle 5 may be swung vertically, being pivotally connected to the plate, and the ends of the arms 2 terminating 15 adjacent the center of the frame when pressure is applied to the handle the mop will be held flat against the floor or other object being operated upon, the frame will not tilt, and the surface will be readily 20 cleaned as the mop fabric is in tight contact therewith. I have provided a novel form 25 of mop in which the fabric is easily removable, the handle being detachable from the frame portion of the mop and the connecting means between the handle and mop frame acting as the means for holding the mop fabric upon the frame. The construction is of a simple character, may be very cheaply made, and the parts easily connected 30 or disconnected.

Having fully described my invention what

I claim as new and desire to secure by Letters Patent is:

1. A mop comprising a looped frame adapted to receive a mop fabric and having 25 inwardly extending parallel arms, a plate having its edges rolled to form eyes through which the arms extend, and a handle pivotally connected to the plate.

2. A mop comprising a looped frame 40 adapted to receive a mop fabric and having parallel arms, a plate provided with openings through which the arms extend and spaced lugs, and a handle pivotally connected to the lugs. 45

3. A mop comprising a looped frame adapted to receive a mop fabric and having parallel arms, a plate having its longitudinal edges rolled to provide eyes through which the arms extend and provided with upwardly extending lugs, and a handle pivotally connected to the lugs. 50

4. A mop comprising a looped frame adapted to receive a mop fabric and having 55 parallel arms, a plate detachably mounted on the arms, a pin extending transversely of the arms and engaging the plate for securing the same upon the arms, and a handle pivotally connected to the plate.

In testimony whereof I affix my signature.

JOHN GLOVER.
